234,125

PIEZOELECTRIC TRANSDUCER ASSEMBLY FOR ULTRASONIC SURVEILLANCE SYSTEM OR THE LIKE

Ralph W. Goble, Eldora, Colo., assignor to
Sontrix, Inc., Boulder, Colo.

Filed May 5, 1972, Ser. No. 250,855

Term of patent 14 years

Int. Cl. D29—99; D14—03
U.S. Cl. D10—104

FIG. 1

FIG. 2

FIG. 3

FIG. 4

FIG. 1 is a perspective view of the piezoelectric transducer assembly for ultrasonic surveillance system or the like showing my new design;

FIG. 2 is a front elevational view, the rear being a mirror image thereof;

FIG. 3 is a bottom plan view; and,

FIG. 4 is a top plan view.

I claim:

The ornamental design for a piezoelectric transducer assembly for ultrasonic surveillance system or the like, as shown or described.
